US0D1017821S

(12) **United States Design Patent** (10) **Patent No.:** **US D1,017,821 S**
(45) **Date of Patent:** **** Mar. 12, 2024**

(54) **MASSAGE APPARATUS**

(71) Applicant: **Biliff Technology (Dongguan) Co., Ltd.**, Dongguan (CN)

(72) Inventor: **Li Yan**, Dongguan (CN)

(73) Assignee: **Biliff Technology (Dongguan) Co., Ltd.**, Dongguan (CN)

(**) Term: **15 Years**

(21) Appl. No.: **29/852,169**

(22) Filed: **Sep. 2, 2022**

(51) LOC (14) Cl. **24-01**

(52) U.S. Cl.

USPC **D24/215**

(58) **Field of Classification Search**

CLAIM

The ornamental design for a massage apparatus, as shown and described.

DESCRIPTION

FIG. 1 is a front perspective view of a massage apparatus, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view shown at an enlarged scale thereof; and, FIG. 8 is a bottom view shown at an enlarged scale thereof. The broken lines in the drawings illustrate the portions of the massage apparatus, which form no part of the claimed design.

1 Claim, 8 Drawing Sheets
